UNITED STATES PATENT OFFICE.

JOHN L. HANLEY, OF CHICAGO, ILLINOIS.

DESIGN FOR A TREAD OF A PNEUMATIC-TIRE CASING.

55,171.

Specification for Design.

Patented May 18, 1920.

Application filed May 12, 1919. Serial No. 296,704. Term of patent 14 years.

To all whom it may concern:

Be it known that I, JOHN L. HANLEY, a citizen of the United States, residing at Chicago, in the county of Cook and State of Illinois, have invented a new, original, and ornamental Design for Treads of Pneumatic-Tire Casings, of which the following is a specification, reference being had to the

accompanying drawing, forming a part thereof.

The figure is a plan view of a tread showing my new design.

I claim:

The ornamental design for a tread of a pneumatic tire casing, as shown.

JOHN L. HANLEY.
